UNITED STATES PATENT OFFICE

AMOS R. BLISS, OF LOWELL, MASSACHUSETTS.

INDUCTION-COIL.

No. 894,479.

Specification of Letters Patent.

Patented July 28, 1908.

Application filed April 13, 1908. Serial No. 426,767.

To all whom it may concern:

Be it known that I, AMOS R. BLISS, a citizen of the United States, residing in Lowell, in the county of Middlesex and State of Massachusetts, have invented an Improvement in Induction-Coils, of which the following description, in connection with the accompanying drawings, is a specification, like letters on the drawings representing like parts.

The present invention relates to an induction coil, and is embodied in a coil of novel construction and arrangement in which the secondary winding is made up of a plurality of separable units, whereby the original manufacture of the coil is facilitated, and the repair of an injured coil is capable of being accomplished without necessarily re-winding the coil, since the defective unit can be replaced by another.

The invention relates further to details of construction and arrangement whereby the complete coil can be assembled and inclosed in a casing having the external contact members and binding posts connected therewith without the necessity of making internal connections.

Figure 1 is a vertical section of a complete coil embodying the invention; and Fig. 2 is a perspective view of one of the units of the secondary winding.

In the construction shown, the secondary consists of four units, these units comprising spools *a* each containing a coil of fine wire *a*² wound thereon, it being practicable to wind the coil by means of an ordinary spooling machine. The spools are provided with central apertures *a*³ of such size and shape as to fit closely upon the primary member *a*⁰ which consists of the core *b* and the low resistance winding *b*² thereon.

The terminals of the high resistance coil unit *a*² are brought through the ends of the spool *a*, and connected with external contact members or springs *a*⁴ which are herein shown (Fig. 2) as pieces of sheet metal connected at one end with the spool and sprung away from the surface of the spool at the disconnected end. These contact members are uniformly arranged on the several spools, so that when the units are assembled

upon the primary member, the contact member at the end of one spool will make electrical contact with the contact member at the end of the adjacent spool, thus connecting the units into a continuous coil from one end of the induction coil to the other.

The coil thus assembled is inclosed in a box or casing *c* which is preferably filled in with paraffin, or similar substance, around the coil after the coil has been placed in position therein. The upper and lower members *c*² and *c*³ of the casing are provided with contact plates or springs *c*²⁰ and *c*³⁰ which are connected through the outside with binding posts or similar terminal devices, contact being made with the final terminals of the secondary coil through the springs on the outer spools.

By this construction, the units of the secondary are complete in themselves, and, at the same time, may be assembled easily, and also incased without trouble, since the electrical contacts throughout are made by simply placing the several parts in their proper position.

Claims.

1. An induction coil comprising a primary winding; and a secondary winding composed of units each of which consists of a coil of wire wound on a spool provided at opposite ends with external contact members connected, respectively, with the terminals of the winding.

2. In an induction coil, the combination with the primary member; of a secondary member consisting of a plurality of units each comprising a spool adapted to fit over the primary member, a winding on said spool, and contact plates located on the outside ends of each spool and connected with the terminals of the wire wound on the spool.

3. In an induction coil, the combination with the primary member; of a secondary member consisting of units having individual coils wound thereon, with external contact devices to connect the windings of adjacent spools; and an inclosing case having internal contact members at opposite ends thereof to engage the contact members at the outer ends of the end spools of the secondary.

4. The herein described unit for a secondary coil which consists of a spool having a central aperture; a coil of wire wound on said spool; and contact members secured to the outer ends of said spool and connected respectively with the two terminals of the coil.

In testimony whereof, I have signed my name to this specification in the presence of two subscribing witnesses.

AMOS R. BLISS.
